UNITED STATES PATENT OFFICE.

WILLIAM H. H. FREEMAN, OF NEWTON, KANSAS.

HARVESTER-REEL.

SPECIFICATION forming part of Letters Patent No. 225,360, dated March 9, 1880.

Application filed January 3, 1880.

To all whom it may concern:

Be it known that I, WILLIAM H. H. FREEMAN, of Newton, in the county of Harvey and State of Kansas, have invented a new and useful Improvement in Reel for a Machine for Cutting Small Grain, of which the following is a specification.

Figure 1 is a perspective view, illustrating my invention. Fig. 2 is a transverse section 10 of reel-shaft, and Fig. 3 is a partial end view.

My invention relates to harvester-reels which are employed for the purpose of pressing backward and holding the stalks of grain in position for being severed by the knives, and 15 which are especially adapted to machines for cutting small grain.

The object of my invention is to construct a reel which shall have sufficient resiliency to prevent the breakage of any of its parts by 20 meeting with some obstacle while the machine is in motion; also to dispense with the usual wood-work, which heretofore has entered largely into the structure of reels; also to provide a reel which will not revolve so long as 25 an obstacle is in the way, although the motion of the machine continues; also to provide means for regulating the spring-power, which will be in opposition to the resistance of any obstacle which the reel may meet with.

To such ends my invention consists, first, in employing a spring in connection with a cam-faced sprocket-wheel, and in the mode of connecting such spring with the reel-shaft; secondly, in the general construction of the reel-beaters and means for connecting them with the reel-shaft; thirdly, in combining spiral springs with the reel-shaft and reel; and, 35 fourthly, in the construction and arrangement of certain detail parts, as herein fully described, and particularly pointed out in the claims.

Referring by letters to the annexed drawings, A designates the reel-shaft, upon which is loosely mounted a sprocket-wheel, B. This 45 wheel is formed with a series of cam-projections, C, upon each one of its sides. A band, D, on the reel-shaft prevents the wheel B from slipping off, this band or strap being secured by a pin, E. A spring, F, which en-

gages with the cams on the wheel B, is secured in place by eyebolts G. The eyes of these bolts are elongated, as shown.

H designates metal straps, which are curled around the reel-shaft and fitted upon the eyes of the bolts, one end of each strap being below and the other end being above the spring.

Wedge-shaped keys I are inserted through the eyes above the straps H, for the purpose of tightening the same down upon the spring.

The eyebolt nearest to the sprocket-wheel 60 passes through a slot in the reel-shaft, whereby the eyebolt and band connected with it may be shifted, so as to vary the power of the spring by increasing or decreasing its length.

The reel-beaters K are made of metal rods, 65 which are bent in proper form and secured to disks L by means of bolts M, which have hooked ends N. The hook portions of these bolts embrace the ends of the beaters K and hold them tightly upon the disks. Each disk 70 L is formed with a sleeve, O, provided with a slot, O', at two points. A pin, P, passes through the reel-shaft, and also through the slots O' in the sleeves O, whereby the disks will have a limited rotary play upon the shaft.

Q designates spiral springs, which are secured to the reel-shaft and to the disks L.

The disks have holes R, into which the ends of the springs are fitted, and by reason of such arrangement the disks may be adjusted 80 upon the reel-shaft, so as to give a twist to the reel.

When the reel encounters any obstacle the springs effectively prevent breakage, which would occur if the parts were rigid. The reel-chain passes around the sprocket-wheel, as 85 usual, and the spring which engages with its cams prevents it from rotating independently of the shaft.

The wheel is made with two sets of cams, so 90 that it may be placed on either end of the shaft and still be serviceable in the manner above described, it being understood that in such case a change of the spring and eyebolts would also be made.

Having thus described my invention, what 95 I claim, and desire to secure by Letters Patent, is—

1. In a harvester-reel, the sprocket-wheel B, with cams upon its sides, in combination with the spring F, substantially as set forth.
2. In a harvester-reel, the sprocket-wheel B, with cams C, the spring F, and eyebolts G, combined substantially as shown.
3. The reel-beaters K and disks L, with sleeves O, having slots O', in combination

with the reel-shaft, spiral springs Q, and pin passed through the shaft and slotted sleeve, substantially as set forth.

WILLIAM H. H. FREEMAN.
